UNITED STATES PATENT OFFICE.

GODFREY ENGEL, OF BALTIMORE, MARYLAND.

DRIVING MECHANISM FOR CENTRIFUGAL MACHINES.

SPECIFICATION forming part of Letters Patent No. 733,377, dated July 14, 1903.

Application filed September 11, 1902. Serial No. 122,932. (No model.)

To all whom it may concern:

Be it known that I, GODFREY ENGEL, a citizen of the United States, residing at Baltimore, State of Maryland, have invented certain new and useful Improvements in Driving Mechanism for Centrifugal Machines; and I do hereby declare the following to be a full, clear, and exact description of the invention, such as will enable others skilled in the art to which it appertains to make and use the same.

My invention relates to improvements in driving mechanism of centrifugal machines, and particularly to improvements in driving mechanisms comprising directly-connected motors, such as electric motors or steam-turbines.

My invention consists in the novel manner of supporting the motor and basket-shaft, whereby free gyration of said shaft and its basket are permitted without disturbing the concentric relation of the rotary and stationary parts of the motor, and in the novel construction of the bearings of the machine, whereby wear may be taken up without disturbing such concentric relation of the said rotating and stationary parts of the motor and without changing axially the position of the rotating member with reference to its surrounding stationary member.

My invention also consists in the means provided for lubricating the bearings and generally in the novel construction of the machine, all as hereinafter set forth in the claims.

In the construction of centrifugal machines it is necessary to provide for gyration of the basket-shaft and basket, so that these parts may find their proper center of rotation. When such machines are driven by directly-connected motors—such, for example, as electric motors—it is most convenient to mount the armature or other rotating member of the motor upon the basket-shaft itself. Since in order that an electric motor may be efficient there must be the smallest possible space between the periphery of its armature and the surrounding field portion of the motor, it is essential that this field shall be so mounted as to gyrate with the shaft. According to my invention both parts of the motor and the basket-shaft are all hung from a suspension-

head having a flexible or universally-jointed support, which permits free gyration of said head and of the parts supported thereby. The weight of the basket-shaft and basket and 55 the contents of the latter is transferred to the suspension-head through supporting means, which may be either internal or external with respect to the basket-shaft. The armature or rotating member of the motor is carried 60 by the basket-shaft, and the field or stationary portion of the motor is carried by the said suspension-head.

The objects of my invention are to improve the construction of the driving mechanism of 65 centrifugal machines, and particularly of centrifugal machines driven by directly-connected motors, to provide for free gyration of the basket-shaft without altering the relative concentric arrangement of the parts of the 70 motor, to provide for taking up wear of the bearings without altering the relative concentric arrangement of such parts of the motor or their relative lateral positions, to improve the means for supporting the weight of 75 the basket-shaft, basket, its contents, and the motor, to lubricate the bearings efficiently, and to make the machine as simple, compact, and durable as possible.

I will now proceed to describe my invention 80 with reference to the accompanying drawings, in which certain forms of centrifugal machines embodying my invention are illustrated, and will then point out the novel features in claims.

In the drawings, Figure 1 shows an elevation and partial section of one form of electrically-driven centrifugal machine having the motor, basket-shaft, and basket suspended from the gyrating suspension-head, as above 85 described, the basket-shaft and basket being supported from said suspension-head by an external suspension-frame. Fig. 2 is a detail view showing, on a larger scale, the upper bearing shown in Fig. 1. Fig. 3 is a detail 90 section illustrating an alternative arrangement of an upper bearing which may be employed in the machine shown in Fig. 1. Fig. 4 shows a vertical section of another centrifugal machine, the basket-shaft, basket, and 95 motor of which are likewise suspended from a gyrating suspension-head, the means by 100

which the basket-shaft and basket are supported being a suspension-rod lying within the basket-shaft, which is hollow.

Referring now to the accompanying drawings, and first more particularly to Figs. 1 and 2 thereof, the machine there shown is suspended from a socket-piece 1, having a substantially spherical socket, by means of a suspension-head 2 of spherical form, fitting within said socket and provided with a suspension-bracket 3, from which the curb 4 of the machine is supported by suspension-rods 5. The basket-shaft 6 is supported from this curb, and therefore from the suspension-head, 15 by means of a spider 7, having supporting and guide bearings for the lower end of said shaft. The bearing by which the upper end of the basket-shaft is guided consists of a bearing-socket 8, formed in the upper end of 20 said basket-shaft, which socket is preferably provided with a bearing-bushing 9 and a stationary taper pindle-pin or spindle 10, fitting into this socket and bushing. This pin is supported and carried by the suspension-head 25 and for purposes of adjustment is screw-threaded and is provided with nuts 11 and 12, by means of which said spindle may be moved up or down with respect to the suspension-head and basket-shaft. To insure perfect 30 centering of the pindle-pin, the adjusting-nuts 11 and 12 are provided with cylindrical and accurately-turned shoulders 13, fitting closely within corresponding recesses in the upper and lower sides of the suspension-head. 35 A lock-nut 14 is also provided.

The shaft 6 carries the revolving member of a motor by which the machine may be driven. The particular motor illustrated is a three-phase induction-motor, the armature 40 15 of which is carried by the shaft 6, the field 16 being secured to the suspension-bracket 2.

It will be observed that as the basket-shaft and basket gyrate during the operation of the machine such gyration takes place from 45 the ball-and-socket suspension-joint as a center, the suspension-head 2 and the curb 4 and motor-field 16 all partaking of this gyration equally with the basket-shaft, basket, and motor-armature. Also, it will be noted, since 50 wear of the bearings is taken up by moving the spindle 10 downwardly by means of the nuts 11 and 12, the armature of the motor remains truly concentric with respect to its surrounding field. For these reasons a very 55 close approach of the armature to the field of the motor is permissible. Also since adjustment for wear is made without moving the armature to one side or the other in the direction of its axis the efficiency of the motor 60 does not decrease with wear of the bearings.

In another application for Letters Patent, filed September 1, 1900, Serial No. 28,852, I illustrated and described and claimed a suspension centrifugal machine having upper 65 and lower bearings constructed substantially as above described except that the pindle-pin of that machine is not adjustable verti-

ally. The machine shown in that application is intended to be belt-driven.

Instead of employing a stationary pindle-pin, as shown in Fig. 1, I may employ the construction shown in Fig. 3, in which the basket-shaft is provided with a tapered journal 17, fitting within a correspondingly-tapered bearing-bushing 18, located within an 75 aperture of the suspension-head, the bearing-bushing being arranged to be adjusted by means of nuts upon screw-studs 19.

One portion of my invention resides in the means employed for oiling the upper bearing of the centrifugal machine. (Shown in Fig. 1.) For this purpose the pindle-pin 10 is provided with a central bore 20, communicating at its upper end with a slot 21 in the side of the pindle which is opposite an oil-hole 22 in the suspension-bracket, to which an oil-cup 23 is connected. Various radial oil-holes 24 radiate from the central oil-passage 20 and serve to supply lubricant to the friction-surfaces of the bearing. The bottom 90 of the bearing-recess in the shaft 6 forms an oil-well and may be drained by means of a passage 25, normally closed at its lower end by a screw-plug 26. An oil-cup 27 surrounds the top of the basket-shaft. In the operation 95 of the machine oil travels upward along the surface of the bushing 9 and pindle 10 by reason of centrifugal action due to the rapid rotation of this shaft and the taper of the pindle-pin, such oil collecting in the oil-cup 10: 27. When the machine comes to rest, this oil will drain backward through oil-holes 24 and central oil-passage 20.

I have shown the machine as provided with a brake mechanism 28, which does not require description. Between the brake and the motor sufficient space is left to permit the installation of an automatic starting device.

Instead of employing external suspension means, comprising side rods 5, the curb 4, and the spider 7, for supporting the basket-shaft and basket from the suspension-head 2, I may employ an internal suspension-rod, as shown in Fig. 4. In this form of machine the basket-shaft (here numbered 29) is hollow, and the 115 suspension-rod 30, suspended from the suspension-head 2, lies within said shaft and is provided at its lower end with the usual bearing for the lower end of the basket-shaft. In this form of machine I prefer to constitute 120 the suspension-rod 30 a bearing-pindle similar to the bearing-pindle 10 of Fig. 1, and for this reason the upper portion of this rod 30 is slightly tapered and fits within a tapered bearing-bushing 31, located within a socket 125 in the upper portion of the shaft 29. Wear is taken up by raising said bushing, which may be done by means of adjusting-nuts on the studs 32. The motor illustrated in connection with this machine is substantially the 130 same as that shown in Fig. 1 and requires no separate description. The curb 33 of this machine may be supported in any suitable manner. I have shown for the purpose the

ordinary suspension-rods 5; but it is not necessary to support the curb in such manner that it gyrates with the basket-shaft if sufficient clearance between the basket-shaft and 5 curb be provided.

Instead of employing an electric motor for driving the basket-shaft other forms of motors may be used.

The lower bearing of the machine shown 10 in Fig. 1 is shielded at the top by a guard or shield 34, which prevents the contents of the basket from entering said bearing as they are discharged from the basket. This guard is secured to the collar 35 of the basket-shaft 15 by the same bolts 36 which secure the basket 37 thereto.

The construction of the lower bearing of the machine shown in Fig. 1 is the same as that shown in my aforesaid application for 10 Letters Patent filed September 1, 1901, Serial No. 28,852.

It is obvious that my invention is susceptible to many variations and modifications and that various forms of bearings may be used. 15 I do not limit myself, therefore, to the particular constructions shown in the drawings and herein described.

What I claim is—

1. In driving mechanism for centrifugal 10 machines, the combination with a revoluble basket-shaft, and a suspender therefor stationary as to rotary motion, but having means of support arranged to permit free gyration of said suspender and of the basket-shaft, of 15 a motor for driving said shaft, located below the point of support of said suspender, and comprising concentrically - arranged members, one carried by said shaft, the other by said suspender.

2. In driving mechanism for centrifugal 10 machines, the combination with a revoluble basket-shaft, and a suspender therefor stationary as to rotary motion, but having means of support arranged to permit free gyration 15 of said suspender and of the basket-shaft, of a motor for driving said shaft, located below the point of support of said suspender, and comprising a rotary member and a stationary member, the latter carried by the gyratory 20 suspender.

3. In driving mechanism for centrifugal 10 machines, the combination with a socket-piece for supporting the machine, a suspension-bracket having a head coacting with said 15 socket, said socket and head arranged to permit free gyratory motion of the bracket, and a basket-shaft revolubly supported by said bracket, of a motor for driving said shaft comprising a rotating member carried by the 20 shaft and a stationary member carried by the bracket.

4. In driving mechanism for centrifugal 10 machines, the combination with a gyrating non-revolving suspender having universally- 15 jointed supporting means, and a basket-shaft 20 revolubly mounted and supported by said suspender, of a motor for driving said shaft,

located below the point of support of said suspender, and comprising a rotating member carried by said shaft and a stationary 70 member carried by the suspender.

5. In driving mechanism for centrifugal 75 machines, the combination with a gyrating non-revolving suspender having universally-jointed supporting means and comprising upper and lower basket-shaft bearings, and a basket-shaft, of a motor for driving said shaft comprising a rotating member carried thereby, located below the point of support of the suspender, and a stationary member carried 80 by the suspender and surrounding the rotating member concentrically.

6. In driving mechanism for centrifugal 85 machines, the combination with a gyrating non-revolving pintle-suspender having flexible or universally-jointed supporting means, and a basket-shaft revolubly carried thereby, of a motor for driving said shaft comprising a rotating member carried thereby and a stationary member carried by the suspender and 90 surrounding the rotating member concentrically.

7. In driving mechanism for centrifugal 95 machines, the combination with a revoluble basket-shaft and a motor for driving the same comprising a rotating member secured to and carried by said shaft and a stationary member surrounding said rotating member, of bearings for said shaft, comprising adjustable self-centering means for taking up wear 100 and preserving a concentric relative arrangement of the revolving and stationary members of the motor.

8. In driving mechanism for centrifugal 105 machines, the combination with a gyrating non-revolving suspender having flexible or universally-jointed supporting means and comprising basket-shaft bearings, and a basket-shaft, of a motor for driving said shaft comprising a rotating member carried thereby and a stationary member carried by the suspender and surrounding the rotating member concentrically; said bearings comprising adjustable self-centering means for taking up wear 110 and preserving a concentric relative arrangement of the revolving and stationary members of the motor.

9. In driving mechanism for centrifugal 120 machines, the combination with a gyrating non-revolving suspender having flexible or universally-jointed supporting means and comprising bearings for the upper and lower ends of a basket-shaft, and a basket-shaft, of a motor for driving said shaft comprising a 125 rotating member carried thereby and a stationary member carried by the suspender and surrounding the rotating member concentrically; said bearings comprising adjustable self-centering means for taking up wear 130 and preserving a concentric relative arrangement of the revolving and stationary members of the motor.

10. In driving mechanism for centrifugal machines, the combination with a gyrating

- non-revolving pintle-suspender vertically arranged, having flexible or universally-jointed supporting means, and provided with bearings for supporting and guiding a revolvable basket-shaft, of a basket-shaft, and a motor for driving the same comprising a rotating member carried thereby and a stationary member concentrically arranged with respect to the rotating member and carried by the suspender; said bearings comprising adjustable self-centering means for taking up wear and preserving a concentric relative arrangement of the revolving and stationary members of the motor.
15. In driving mechanism for centrifugal machines, the combination with a revolvable basket-shaft, and a gyrating non-revolving suspender supporting the same and having bearings therefor, of a motor for driving said shaft comprising a rotating member secured to and carried by the shaft and a stationary member carried by said suspender and concentrically arranged with respect to said rotating member; the bearings for said shaft comprising a stationary member fitting within a corresponding revolving member, the latter provided with a split bushing and taper thread for the purpose of diminishing the bore of the same and for taking up wear.
20. 12. In driving mechanism for centrifugal machines, the combination with a revolvable basket-shaft, and a motor for driving the same comprising a rotating member secured to and carried by the shaft and a stationary member surrounding said rotary member, of bearings for said shaft comprising an adjustable tapering stationary member fitting a correspondingly-tapered revolving member, said adjustable member being movable for the purpose of taking up wear, and being arranged to preserve a concentric relative arrangement of the revolving and stationary members of the motor.
25. 13. In driving mechanism for centrifugal machines, the combination with a revolvable basket-shaft, and a motor for driving the same comprising a rotating member secured to and carried by said shaft and a stationary member surrounding said rotary member, of bearings for said shaft comprising a stationary journal fitting within a bearing-socket of said shaft, both journal and bearing tapering toward the opposite end of the shaft, and means for taking up wear.
30. 14. In driving mechanism for centrifugal machines, the combination with a revolvable basket-shaft, and a motor for driving the same comprising a rotary member secured to and carried by said shaft and a stationary member surrounding said rotary member, of bearings for said shaft comprising a stationary journal fitting within a bearing-socket of said shaft, both journal and bearing tapering toward the opposite end of said shaft, and the journal being axially adjustable.
35. 15. In driving mechanism for centrifugal machines, the combination with a revolvable basket-shaft, and a supporting-bearing therefor, said shaft having also a tapering bearing-socket for the reception of a pintle-pin, of a taper pintle-pin, a bracket for supporting the same, and adjusting-nuts for said pin having cylindrical portions fitting within corresponding recesses of said bracket, and serving to center said pin.
40. 16. In driving mechanism for centrifugal machines, the combination with a revolvable basket-shaft having in one end a downwardly-tapering bearing-socket, of a stationary taper pintle fitting within said socket, said pintle being provided with a longitudinal oil-passage and with branch passages extending to the outer surface of said pintle, means for supporting said pintle, and an oil-cup surrounding said pintle and the orifice of said bearing-socket.
45. 17. In driving mechanism for centrifugal machines, the combination with a revolvable basket-shaft having in one end a downwardly-tapering bearing-socket, of a supporting-bracket, a taper pintle supported thereby but axially adjustable with respect thereto, and having a longitudinal oil-passage, branch passages extending therefrom to the outside of said pintle, and a slot, communicating with said longitudinal passage but in registry with an oil-passage of said bracket, and an oil-cup surrounding said pintle and the orifice of said bearing-socket in said shaft.
50. 18. In a driving mechanism for centrifugal machines, the combination with a revolvable basket-shaft, and a suspender therefor stationary as to rotary motion, but having means of support arranged to permit free gyration of said suspender and of the basket-shaft, and having upper and lower bearings for said shaft, the latter below the position of the basket on said shaft, of a shield surrounding the upper end of said lower bearing and serving to prevent material from the basket from entering said bearing.
- In testimony whereof I affix my signature in the presence of two witnesses.
